DESIGN FOR A COMBINATION PEN RACK AND DESK UNIT

Paul Rossi, Warren, Ohio

Application July 9, 1946, Serial No. 131,425

Term of patent 14 years

(Cl. D74—1)

To all whom it may concern:

Be it known that I, Paul Rossi, a citizen of the United States of America, residing at Warren, in the county of Trumbull and State of Ohio, have invented a new, original, and ornamental Design for a Combination Pen Rack and Desk Unit, of which the following is a specification, reference being had to the accompanying drawing, forming part thereof.

Figure 1 is a front perspective view of a combination pen rack and desk unit showing my new design, the images shown thereon being merely representative and not intended for any particular individuals.

Figure 2 is a rear perspective view of the same

but on a reduced scale in comparison with the disclosure in Figure 1.

I claim:

The ornamental design for a combination pen rack and desk unit, as shown and described.

PAUL ROSSI.
